UNITED STATES PATENT OFFICE.

JONATHAN P. ABBOTT AND WILLIAM H. TRISSLER, OF CLEVELAND, OHIO.

IMPROVEMENT IN EAVES-TROUGH HANGERS.

Specification forming part of Letters Patent No. 172,841, dated February 1, 1876; application filed July 6, 1875.

To all whom it may concern:

Be it known that we, JONATHAN P. ABBOTT and WILLIAM H. TRISSLER, of Cleveland, in the county of Cuyahoga and State of Ohio, have invented a certain new and Improved Eaves-Trough Hanger, of which the following is a full and complete description, reference being had to the accompanying drawings, making part of this specification, in which—

Figure 1 is an end view of an eaves-trough and the hanger attached thereto. Fig. 2 is a plan view. Fig. 3 is a detached view of the hanger. Figs. 4 and 5 are modifications of Fig. 3.

Like letters of reference refer to like parts in the several views.

This invention is a device for hanging eaves-troughs, the construction and application of which are as follows:

In the drawing, A represents a section of the eaves-trough, which is or may be like that in ordinary use. B is a cross-bar, one end, E, of which is bent around the bead C of the trough, whereas the opposite end extends across the trough, just to the inside thereof. To the top of said end is firmly secured a finger, D, composed of soft or flexible metal.

It will be seen, in Fig. 3, that between the finger and the end of the bar there is a narrow space, *a*, of about the width of the thickness of sheet-tin, and that the end of the finger is bent down below the end of the bar, and a little distance therefrom.

The bar is attached to the trough as follows: The inner edge of the trough is left straight in the line of its curve—that is to say, the edge is not bent inward, as shown at *b*, but continues on in the curve-line, as indicated by the dotted line *c*, Fig. 1. This inner edge of the trough is inserted between the finger D

and the end of the bar, in the space *a*. In order to do this the bar is held up endwise. The bar is then bent down to a horizontal position, bringing the end E upon the bead C, around which it is then bent, as shown in Fig. 1, whereby that side of the trough is secured.

In the act of bringing down the bar to a horizontal line the edge *c* of the trough is bent inward to a horizontal line, as seen at *b*, Fig. 2, forming a right-angled hook that laps on the end of the bar, and which is prevented from slipping therefrom by the lip *d* of the finger, which, by a proper tool, is pressed down over the end of the bar, thereby locking the edge of the trough to the bar, as shown in Fig. 1.

To the bar B is riveted the strap F, whereby the trough is fastened to the roof. Fig. 4 is a modification of Fig. 3, in which a finger is formed by cutting into the end of the bar two incisions, forming a finger, *e*, of the metal of the bar, instead of making it of a separate piece, as is the finger D above described.

Fig. 5 represents the finger as made of a strip of metal of sufficient length to form also a strap whereby to attach the trough to the roof.

What we claim as our invention, and desire to secure by Letters Patent, is—

The bar B, having the inner end bifurcated by attaching a curved finger, D, and the outer end curved to clasp the bead of a trough, in combination with said trough and the holding-strap F, all constructed substantially as and for the purpose described.

JONATHAN P. ABBOTT.
WILLIAM H. TRISSLER.
